To all whom it may concern:

Be it known that we, WILLIAM E. BALL and ALICE C. Our invention has relation to a new and original design for curtain-holders, the object of which is to provide suitable and inexpensive means for connecting or securing the curtain to its pole and preventing its accidental disconnection therefrom.

In the accompanying drawings, Figure 1 is

The leading features of the design consist in a metallic strip formed near its end with heart-shaped openings 1, provided with inwardly and downwardly projecting V-shaped points 2, the extreme ends of said strip being 25 rounded and bent outwardly.

What we claim is—
